UNITED STATES PATENT OFFICE

1,925,747

LIQUID LEVEL INDICATOR

Ettore Caretta, Turin, Italy

Application June 10, 1929, Serial No. 369,606, and
in Italy June 19, 1928

4 Claims. (Cl. 73—82)

The present invention relates to devices intended to detect the level of a liquid contained in a receiver of the kind comprising a control member mounted to move vertically in said receiver and actuated from the outside, said member being stopped at the time it abuts on a float which follows the level of the liquid.

The present invention has for its object a device of this kind which comprises means for stopping immediately and for easily releasing said movable control member, such results being secured by the fact that the said movable control member on reaching the float, locks the latter by exerting on it an action which jams said float on a part guiding it, while the conditions of engagement of said movable control member and float are such as to permit the control member of producing its action without becoming jammed with the float.

On the annexed drawing are illustrated by way of example some embodiments of the present invention and

Figure 1 is a diagram of a level indicator mounted in a receiver;

Figure 2 illustrates separately in central section the essential parts of an embodiment of the device of this invention;

Figure 3 is a central section of the parts of a device comprising an annular float guided on a central rod;

Figure 4 is a sectional view on line 4—4 of Figure 3;

Figure 5 is a central section of a device in which the float is mounted within a tube;

Figure 6 shows a modified construction;

Figure 7 is a sectional detail view to an enlarged scale of the end part of the movable member intended to act on the float.

In the level indicator arrangement shown in Figure 1, 1 is the top wall of a receiver in which is secured a vertical guide rod 2. Said guide rod is encircled by an annular float 3, having a central lining sleeve 8, which is able to move freely along it. Said guide rod 2 is hollow and has a longitudinal slot 4 and in said hollow rod 2 is free to move a metal wire or cable 5 which extends outside of hollow rod 2 and has its free end connected with a manipulating member 19 adapted to slide along a guide member 20 having a scale 21; a sheath 18 encircles said cable 5 and has its ends abutting on top end of hollow rod 2 and guide 20 as conventional in flexible transmissions. The end of cable 5 lying within the hollow guide rod 2 has a head 5' guided to reciprocate within hollow

rod 2 and provided with a transverse arm 6 extending through slot 4 and carrying an outer downward projection on 7. Arm 6 is thus caused to move along hollow rod 2 while standing substantially perpendicular to the axis of rod 2 owing to the guide afforded by head 5' within bore of hollow rod 2.

In operation, when the manipulating member 19 is manipulated to move down the arm 6, the projection 7 of said arm produces an eccentric thrust on float 3, and said action causes float 3 to swing into the position shown in dotted lines the angle of swinging being exaggerated in the drawing for purpose of illustration; thus a jamming action of the edges of the internal sleeve or lining 8 of the float on the surface of the guide rod 2 is produced and float 3 is locked on said guide rod 2, arm 6 with cable 5 and manipulating member 19 being prevented from being further moved down by the engagement of projection 7 with float 3 and by the guide afforded by hollow rod 2 to head 5' which prevents said arm 6 from rocking with respect to hollow rod 2; the manipulating member 19 is thus stopped along scale 21 in a position giving an indication as to the level of the liquid in the receiver.

The same result may be secured in improved conditions, both as to the construction of the apparatus and to its operation, by securing the necessary cooperation of the float and feeling member which is inside the tubular rod 2, by means of a member carried by the float and entering the slot of the tubular rod 2 to receive the action of said operating member.

Figure 2 shows an embodiment of a level indicator according to this invention in which the above stated condition is secured. In this construction the sleeve 8 of float 3 comprises projecting arms 9 in which is journalled a roller 10 which is free to extend into hollow guide rod 2 through slot 4 of the same while the member manipulated by operator consists of a plunger 11 which on coming in contact with roller 10, causes it to move outwardly and therefore causes the float 3 to rock, it receiving a thrust whose line of action does not pass through the center of buoyancy of said float, and to be jammed by the opposed edges of its sleeve 8 on the guide rod 2. The provision of a roller 10 for cooperation with the plunger 11 has, with respect to the use of a member arranged in stationary manner on the float, the advantage that the upward or release motion of said plunger is assisted by the fact that the engagement between the roller 10

and the plunger 11 is frictionless or rolling in character.

Figures 3 and 4 show another construction of a level indicator according to this invention in which the roller 10 is located in a recess 22 of float 3 which has a comparatively large extent in a direction parallel with guide rod 2, while said sleeve 8 has its bore enlarged on a portion of its longitudinal extent as shown by 8' to produce a narrower region 8'' for engagement with the rod 2 whose top and bottom edges 8a-8b are intended to come into jamming contact with the guide rod 2.

As above referred to, roller 10 makes easy the release of plunger 11 and therefore said plunger cannot become jammed with the float.

In the construction of Figure 5, the float 3 is mounted within a tube 12 and it comprises a radial arm 13 extending into the central hollow rod 2 through the slot 4 of the same, said hollow rod 2 operating as a guide for a plunger 11 connected with the wire or cable 5.

Figure 6 shows a construction in which an annular float 3 is mounted on a solid guide rod 15 and carries a radial arm 13 extending into a slotted tube 2 along which the plunger 11 is mounted to move.

In the constructions of Figures 5 and 6 when the plunger 11 acts on the arm 13, float 3 receives an eccentric action and therefore it is caused to swing and take up a position in which it is jammed within the tube 12 or on rod 14 respectively and is locked thereon; also in these constructions the action of the plunger 11 on the arm 13 is such as to prevent any possible jamming interaction of said plunger 11 and arm 13.

In any case the manipulating member 19 cannot be shifted after the end part 11 of the cable 5 has engaged the float 3 and it is thus in conditions to show the level of the liquid on the scale 21.

The end of the wire or cable is preferably provided with a hollow plunger 16 shown in detail in Figure 7 which is engaged on enlarged knob 17 provided at the end of the cable or wire 5. For this purpose a plunger 16 is availed of which has cylindrical recess 16' having a depth larger than longitudinal length of knob 17; knob 17 is introduced into said recess 16' and then the edge of the mouth of said recess is crimped over said knob 17 as at 16'' to engage it in said recess 16' of plunger 16; said plunger 16 has conveniently a tapering shape in its region intended to engage roller 10 as illustrated.

The feeling member consisting of cable 5 and plunger 16 may be freely inserted and removed in and from tubular guide rod 2 without interference by the float or members carried thereby.

The described device provides for locking the manipulating and indicating member 19 in a position in register with the liquid level by taking advantage of the float as a clamping member, this result being secured in conditions such as said movable member must merely produce a thrust and it is never required to heavily engage

another member thus removing any possible jamming of said member and reducing to a minimum the pull required to move it up.

What I claim as my invention and desire to secure by United States Letters Patent is:

1. An indicator for indicating the level of a liquid in a receiver comprising a tubular rod having a slot therealong, an annular float encircling said tubular rod and movable along it, a member journaled on said float and extending into said tubular rod through said slot of the same, a feeling member mounted to move in said tubular rod for engagement with said journaled member, a manipulating member for actuating said feeling member and indicating means moving in unison with said manipulating member. 90

2. An indicator for indicating the level of a liquid in a receiver comprising a tubular rod having a slot therealong, an annular float encircling said tubular rod and movable along it, said float bearing on said tubular rod by a comparatively short span in the direction of the axis of said tubular rod, a roller journaled on said float at a point at a comparatively large distance from the middle point of said float region and extending into said tubular rod through said slot of the same, a feeling member mounted to move in said tubular rod for engagement with said roller, a manipulating member for actuating said feeling member and indicating means moving in unison with said manipulating member. 95

3. An indicator for indicating the level of a liquid in a receiver comprising a guide rod, an annular float encircling said guide rod, a sleeve in the central bore of said annular float, said sleeve having a surface for engagement with said guide rod which is shorter than the float size in the direction of the axis of said guide rod, a feeling member mounted to move along said guide rod, a manipulating member for actuating said feeling member, indicating means moving in unison with said manipulating member and frictionless cooperating means on said float and feeling member to tilt said float and clamp said sleeve and float on said guide rod on engagement of said means to stop said feeling member. 110

4. An indicator for indicating the level of a liquid in a receiver comprising a tubular rod having a slot therealong, an annular float encircling said tubular rod and movable along it, said float embracing said tubular rod by a region which has a comparatively short span in the direction of the axis of said tubular rod, a member journaled on said float at a point at a comparatively large distance from the middle point of said float region and extending into said tubular rod through said slot of the same, a feeling member mounted to move in said tubular rod comprising a flexible member and a tapering plunger for engagement with said journaled member, a manipulating member for actuating said feeling member and indicating means moving in unison with said manipulating member. 125
